UNITED STATES PATENT OFFICE.

WILLIAM S. VETTER, OF NEW YORK, N. Y., ASSIGNOR OF ONE-HALF TO JOHN J. BARBER, OF BROOKLYN, NEW YORK.

CASE-MAKING MACHINE.

1,078,527.

Specification of Letters Patent. Patented Nov. 11, 1913.

Application filed May 18, 1912. Serial No. 698,209.

To all whom it may concern:

Be it known that I, WILLIAM S. VETTER, a citizen of the United States, residing at New York city, in the county of New York 5 and State of New York, have invented certain new and useful Improvements in Case-Making Machines, of which the following is a full, clear, and exact specification.

This invention relates to case making machines, and is particularly directed to case making machines capable of ready adaptability for varying the width of the back-lining strip of book covers, and also for securing economy in the amount of paper-board 15 or other material used in making up book covers.

More specifically, this invention is directed to improvements in case making machines whereby a continuous strip of paper 20 or like material of the width of the desired back-lining strip is fed by suitable mechanism in proper relation to be picked up by the suction cup and automatically cut the desired length, which mechanism is preferably adjustable to adapt the same to varying widths of backs of the cases to be produced. By means of my invention, the paper or like material is fed as a continuous strip, through guides of a novel construction, 25 usually supported by the inside bars of the cover board feeding mechanism, and suitable mechanism provided for simultaneously adjusting the said inside bars and guides. By my invention the necessity of employing 30 trimming knives is obviated and great economy in the amount of paper used in making the case or cover is effected as well as increasing materially the output of the case making machine.

40 Other features and advantages of my invention will be readily understood from the following description, and the accompanying drawings, in which—

Figure 1 is a perspective of a case making 45 machine embodying my invention; Fig. 2 is a detail sectional view taken on the line 2—2 of Fig. 1; Fig. 3 is an enlarged detail showing my adjustable guides in perspective; and Fig. 4 is a detail sectional view of the 50 knife and rolls for guiding the strip of back lining paper therethrough.

Referring to the drawings, Fig. 1 represents the end portion of the Smyth type

of case-making machine at which the magazines for the cover boards are positioned. 55 In this type of machine, as shown in Jacobs United States Patent No. 580,111, dated April 6, 1897, the boards are fed one at a time by suitable apparatus from the bottom of each of two of the magazines, the two 60 boards thus fed being moved along two pairs of parallel, mutually adjustable guide-bars to a point where the two boards and the back-lining strip, disposed intermediate of the same, are picked up by a suction-cup, 65 and placed on adhesive-coated-buckram, linen or other suitable covering, and then piled up at one end of the machine. When the size of the covers is varied, the magazines are adjusted to accommodate the dif- 70 ferent size of the side-boards, and the two pairs of adjustable guide-bars are correspondingly varied, that is, the distance between the bars of each pair, and the distance between the inside bars of the two pairs. 75 The supporting frame for the magazines and the adjustable guide-bars is indicated in Fig. 1 and comprises the end members 1, 2 connected by the transverse members 3, 4. The uprights of one magazine are indicated 80 at 5, 6; the other magazine is formed of the inner upright 7 and the outer upright 8, the latter being largely broken away in order to show other parts of the device more clearly. The outside bar 9 and the inside bar 10, pro- 85 vided respectively with ledges 11, 12 facing one another, form one pair of guide-bars for feeding cover-boards for one side of the covers. The inside bar 13 and the outside bar 14, similarly provided with oppositely 90 facing ledges, forms the other pair of guide-bars for feeding cover boards for the other side of the covers. In order to secure the proper feeding of the cover-boards, the in- 95 side guide-bars are provided respectively with springs 10', 13' (see also Fig. 2), whereby the cover boards are yieldably held in position against the outside guide-bars. In this type of case-making machines, suit- 100 able adjusting means is provided, described more fully hereinafter, whereby for less width of cover, the bars of each pair of guide-bars are moved closer together, and for greater widths of cover, the guide bars of each pair are moved farther apart; when 105 the thickness of the books is increased or

decreased, the distance between the inside guide-bars is correspondingly increased or decreased.

The paper or like material to be supplied to the machine for forming the back-lining of the case is fed, in accordance with my invention, as a continuous strip 15 from the roll 16 rotatably mounted in the brackets 17, the continuous strip 15 having the width of the back-lining of the case. The strip 15 is fed over the roller 18 below the bar 3, thence between the flanges 19, 20 of the oppositely disposed guides 21, 22, thence between the slots 23, 24 of the guides 21, 22, and under the bar 4, between the rollers 25, (see Fig. 4) between the blades of the knife 26, and finally on a level with the ledges 11 and 12. The rollers 25 are driven by gears 35 intermittently to feed the proper length for the back-lining strip. Thus the movement of the strip 15 on the top of the table of the machine is in a direction opposite to the direction in which the boards from the two magazines are fed. As shown, the guide 21 is mounted on the bar 10, and the guide 22 is mounted on the bar 13, said bars being adjustable relative to one another by suitable regulating mechanism. I have shown one form of such regulating mechanism in Fig. 1, comprising the right and left-hand screws 27, 28 connected together through the shaft 29 and suitable gearing, and regulated by the crank 30. The outside bars 9, 14 are also mounted adjustable on the cross-bars 3, 4, and may be provided with separate screw shafts and crank, if desired. The adjustable guides 21, 22 are shown as having forward slots 19, 20 formed of a lower flange 31 and an upper adjustable flange 32, and extensions projecting toward the rear of the machine, and at or near their rear ends are provided with slots 33. By reason of the forward slots 19, 20 being connected to the rear slots 33 by extensions somewhat resilient, but having sufficient stiffness to take up the slack of the strip 15, in cooperation with the rollers by which said strip 15 is fed to the top of the machine, improved results of marked value are secured. When it is desired to vary the width of the back-lining strip, the crank 30 is turned to move the bars 10, 13 the desired distance apart, and at the same time securing adjustment of the guides 21, 22 with respect to one another. It will be noted that each guide 21, 22 is formed of angled forward portions so arranged with respect to one another that the guiding flanges 31, 32 project inwardly from the bars 10, 13 to provide a proper clearance at the top of the bars 10, 13 to allow the suction cup to transfer the back-lining strip to the adhesive coated case-covering, as will be understood. For such use where the dimensions of the back-lining strip are frequently varied, a number of

rolls 16 carrying different widths of strips are so arranged that the desired roll can be moved in alinement with the roller 18 and guides 21, 22, or the roll of desired width of strip substituted in the bracket 17, 17.

By this invention, the usual cutting knives are done away with, and also the disadvantages incident to adjusting such cutting knives and sharpening the same are obviated, as well as avoiding delays due to loosening of the usual rubber washers and to frequent replacing such parts due to wear. Besides, the inconvenience and difficulties due to the heaping of the cut-off edges of paper are overcome, and economy in the amount of paper used effected.

It will be understood that changes or modifications in the specific arrangement illustrated may be made without departing from this invention.

Having thus described my invention, I declare that what I claim as new and desire to secure by Letters Patent, is:—

1. A case-making machine, comprising the combination of a plurality of pairs of guide-bars for guiding cover boards, said guide-bars being arranged side by side, means for adjusting said guide-bars relative to one another, cutting means disposed transverse to said pairs of guide-bars, means to feed a continuous strip of paper from a given point through said cutting means and to a position adjacent certain of said guide-bars to provide the back lining strip of the case, and a plurality of guiding elements for controlling the displacement of the back lining strip laterally relative to said certain guide-bars, said plurality of guiding elements being stationary with respect to said certain guide-bars and disposed intermediate said given point and said cutting means.

2. A case-making machine, comprising the combination of a plurality of pairs of guide-bars for guiding cover boards, said guide-bars being arranged side by side, means for adjusting said guide-bars relative to one another, cutting means disposed transverse to said pairs of guide-bars, means to feed a continuous strip of paper from a given point through said cutting means and to a position adjacent certain of said guide-bars to provide the back lining strip of the case, and a plurality of guiding elements for controlling the displacement of the back lining strip laterally relative to said certain guide-bars, said plurality of guiding elements being individually and stationarily carried by said certain guide-bars and disposed intermediate said given point and said cutting means.

3. A case making machine, comprising the combination of a plurality of pairs of guide-bars for guiding cover boards, said guide-bars being arranged side by side, means for adjusting said guide-bars relative to one an-

other, cutting means disposed transverse to said pairs of guide-bars, means to feed a continuous strip of paper from a given point through said cutting means and to a position adjacent certain of said guide-bars to provide the back lining strip of the case, a plurality of oppositely facing guiding elements for controlling the displacement of the back lining strip laterally relative to said certain guide-bars, each of said plurality of guiding elements comprising two guiding flanges stationary with respect to said certain guide-bars and disposed intermediate said given point and said cutting means, and means for adjusting the guiding flanges of each guiding element with respect to one another.

4. A case-making machine, comprising the combination of a plurality of pairs of guide-bars for guiding cover boards, said guide-bars being arranged side by side, means for adjusting said guide-bars relative to one another, cutting means disposed transverse to

said pairs of guide-bars, means to feed a continuous strip of paper from a given point through said cutting means and to a position adjacent certain of said guide-bars to provide the back lining strip of the case, a plurality of oppositely facing guiding elements for controlling the displacement of the back lining strip laterally relative to said guide-bars, said guiding elements being individually carried by said certain guide-bars, each of said guiding elements comprising two guiding flanges and disposed intermediate said given point and cutting means, and means for adjusting said guiding flanges of each guiding element with respect to one another.

In testimony whereof I affix my signature, in presence of two witnesses.
